(57) **CLAIM**

The ornamental design for a bag with a face decoration, as shown and described.

DESCRIPTION

FIG. 1 is front elevational view of a bag with a face decoration showing our new design as applied on the side of a bag.

FIG. 2 is a rear elevational view thereof.

FIG. 3 is a left side elevational view thereof.

FIG. 4 is a right side elevational view thereof.

FIG. 5 is a top plan view thereof.

FIG. 6 is a bottom plan view thereof; and,

FIG. 7 is a front elevational view thereof showing a tongue portion of the decoration withdrawn behind two zippers.

The dashed broken lines that appear in FIGS. 1 and 7 depict stitching lines which are part of the claimed design. The dotted broken lines in the figure drawings are included for the purpose of illustrating environment and form no part of the claimed design. The dot-dash broken lines that appear in FIGS. 1 and 7 form the boundary of the claimed design, which also forms no part of the claimed design.
